UNITED STATES PATENT OFFICE.

JOSEPH H. JACOBS, OF ROCHESTER, NEW YORK.

CURLING-IRON ATTACHMENT.

Application filed October 3, 1927. Serial No. 223,604.

This invention relates to improvements in curling irons of the type employed in waving or marcelling ladies' hair and has reference more particularly to the addition of guard means for protecting the person on whom the device is used from being burned.

Curling irons of the type to which this application refers are provided with two members connected together in the manner of a tong, one of these members is formed from a cylindrical bar of metal and the other from a piece of thin metal bent transversely into U-shape so as to form an elongated groove for the reception of the other member.

In using these tongs great care must be exercised by the operator so that neither the metal bar nor the edges of the U-shaped member will come into contact with the scalp as they are hot and will cause burns.

It is the object of this invention to produce curling devices of this kind with means that will prevent the hot parts from coming into contact with the scalp of the person whose hair is being curled thereby making it possible to employ these devices without fear of causing injury and which can therefore be brought into contact with the scalp without danger.

It is another object of this invention to produce a device of this kind that shall be of simple construction and which will therefore be inexpensive to manufacture.

It is a still further object of this invention to produce a protector that can be readily applied to curling devices of ordinary construction and which can therefore be sold as attachments.

The above and other objects that may become apparent as this description proceeds are attained by means of a construction and an arrangement of parts that will herein-after be described in detail and reference for this purpose will now be had to the accompanying drawing in which the preferred embodiment thereof has been illustrated and in which:

Fig. 1 shows a side elevation of a curling device which has been provided with my protective device;

Fig. 2 is a perspective view showing the protector that is attached to the cylindrical heating element of the device illustrated in Fig. 1;

Fig. 3 is a section taken on line 3-3, Fig. 1;

Fig. 4 is a side elevation of a portion of

a curling device of the type illustrated in Fig. 1 and shows a slightly modified form of protector;

Fig. 5 is a transverse section taken on line 5-5, Fig. 4;

Fig. 6 is a fragmentary detail showing a slightly modified form of construction;

Fig. 7 is a side elevation of the cylindrical heating element, shown in the device illustrated in Fig. 1, and shows the protector in place thereon, the protector has been shown partly in section so as to better illustrate the construction; and

Fig. 8 is a side elevation partly in section of a slightly different form of a curling device showing my protectors applied thereto.

Numeral 1 represents the cylindrical heating element of a curling device. This heating element is tubular and contains an electric resistance wire by means of which the heat is generated. This has not been shown as it is a very common construction. Secured to one end of the heating element is a handle 2 which is provided with a metal ferrule 3. A cooperating jaw member 4, which is formed of thin metal bent transversely into the shape shown in Fig. 3, is pivotally connected at 5 to a sleeve 6 that encircles the heating element 1 and holds the member 4 in place thereon. A spring 7 is attached to the pivot 5 and is provided with an opening for the reception of the screw 8 by means of which the parts are held in assembled position. A handle portion 9 which is integral with the part 4 extends rearwardly and carries a thumb piece 10 of heat insulating material. When pressure is applied to the thumb piece, the member 4 can be rotated about the pivot 5 so as to move it away from the heating element somewhat in the manner of a pair of tongs.

It will be seen from Fig. 3 that the member 4 has its side edges extending down beyond the heating element 1 and these edges are flared outwardly. As the member 4 comes either into direct contact with or into close proximity to the heating element 1, it becomes very hot with the result that if the edges come in contact with the scalp, they will cause burns. In order to keep the extreme edges of the member 4 from getting excessively hot, I have provided longitudinal slots 11 which extend substantially the entire length of the clamping member. These slots are so long that they leave only a very thin section of material at points 12 and 13. The metal portions 15 that form the outer edges of the

108

109

110

clamping member must therefore receive all their heat by conduction through the connecting sections 12 and 13 and as these have very small sectional areas, only a small amount of heat will be conducted to the parts 15 with the result that they never become very hot. It is possible by this means to keep the parts 15 at such low temperature that they will cause no injury if they come in contact with the scalp of the person whose hair is being curled.

In using this device it is necessary to insert locks of hair between members 1 and 4 and the most convenient way of doing this is to slide the heating element 1 along the scalp, thereby causing it to penetrate between the hair. If this is done, however, burns are liable to result for the reason that the heating element is always very hot. With a device of this type as usually constructed, it is therefore essential that the operator shall exercise great care to keep the metal parts from coming into contact with the skin of the person whose hair is being curled. In order to prevent injury from the heating element 1, I have provided the same with a protector 16, which is formed from a bar of insulating material, shaped somewhat like that shown in Fig. 2. This bar has a cross section substantially like that shown in Fig. 3, and is provided at its outer end with a conical portion 17, which extends to one side of the flat surface 18. This conical portion has a conical recess 19, which is adapted to receive the point 20 of the heating element 1 in the manner shown most clearly in Fig. 7.

For the purpose of holding this protector bar in place, I have provided a ring 21 that is placed around the heating element 1 between the sleeve 6 and the ferrule 3 in the manner shown in Fig. 1. A coil spring 22 has one end secured to the end of the protector bar 16 in the manner shown in Fig. 7 and has its other end provided with a hook 23 that engages the ring 21 in the manner shown in Fig. 2. When the protector is applied the hook 23 is connected with the ring 21 and the spring 22 extended sufficiently to permit the point 20 of the heating element to be inserted into the recess 19. The tension of the spring 22 will then hold the protector 16 in place in the manner shown.

Attention is called at this point to the fact that the protector 16 is bowed so that the surface 18 which lies adjacent to the heating element 1 contacts with the latter only at the ends of the bar in the manner shown in Fig. 7. From Fig. 7 it will also be seen that the recess 19 has a greater taper than the end 20 of the heating element so that the edges of the part 17 will only come in contact with the heater, leaving a space between the surface of the end 20 and the interior surface of the recess 19 in the manner shown. This reduces the capacity for conducting heat and serves to keep the end of the protector cooler than it

would be if the entire surface of the recess came into contact with the heater.

In order to further decrease the transference of heat from the heater to the end 17, I have provided openings 24 which permit air to circulate through the recess and this also retards the heat transfer. The protector shown in Fig. 2 can be manufactured as an accessory and can be attached to any curling device constructed like that shown in Fig. 1 by merely removing the clamping member 4, inserting the heater through the ring 21 and reapplying the clamping member until the parts assume the position shown in Fig. 1. The tip 20 is then merely inserted into the recess 19 and the protector will thereby be held in place.

Instead of providing the longitudinal slots 11 for the purpose of preventing the parts 15 from becoming heated, it is possible to provide the outer edges with bars of poor heat conducting material such as those indicated by reference numeral 25, in Figs. 4 and 5. When this construction is employed the bars 25 have their ends provided with slots 26, which are engaged by the projections 27 that extend from the clamping element 4 in the manner shown. These slots should be deep enough so that the metal forming the parts 27 will not come in contact with the scalp when the device is in use.

It is obvious that the protector 16 can be secured to the heating element in many different ways and in Fig. 6 I have shown an example of such a modification. In this construction the sleeve 6^a which corresponds to sleeve 6 in Fig. 1 is provided with a spring tongue 28, whose outer end is provided with a hook 29 that engages a notch 30 in the protector 16. The other end of the protector is formed exactly like that shown in Fig. 7 and it can be readily applied by merely sliding the inner end underneath the tongue 28 until the parts are in the position shown.

As above intimated many other ways of securing the bar can easily be devised and I want it understood that the examples shown and described are illustrative of means for this purpose only and are not intended to be considered as in any way limiting the invention to these specific devices.

In the above parts of the specification, I have illustrated my invention connected with one form of a curling device and in order to show its adaptability to other forms, I have shown in Fig. 8 a side elevation of a slightly different form of a curler. In this device the bars 31 correspond to some extent to the heating element 1, in Fig. 1, but are merely solid metal bars which are not provided with any heating devices. The heater in this modification is located in the channel 32 between the two parts of the clamping member 4^a. Heat protectors 25 are secured to the edges of the clamping member 4^a in the manner shown in

Fig. 4, or the edges may be provided with slots 11 in the manner shown in Fig. 1. Protectors 16 are secured to the bars 31 substantially in the manner described, but instead of the coil spring 22 and the ring 21, I have provided bent spring wire members 33, one end of which is secured to the end of each protector bar 16 and the other end of which is inserted through a hole 34 in the bars 31. The 10 protectors 16 serve to separate the hot bars 31 from the scalp while the device is in use, all in the manner above explained.

From the above it will be apparent that I have provided a simple means for protecting the user against injury from the heated parts of the curling device and that my invention is so constructed that it can be readily applied to curling devices of ordinary construction.

Having described my invention what I claim as new is:

1. A hair curling device having a member of heat conducting material, means for heating said member, a protector comprising a member of poor heat conducting material extending along the heated member and means for detachably securing the protector in place.

2. A hair curler comprising a member of heat conducting material, means for heating said member and a protector detachably secured thereto, said protector comprising a bar of poor heat conducting material.

3. A curling device comprising two relatively movable members, one of which has an opening containing an electrical resistance, and the other of which is provided with a recess for the reception of first mentioned member, both of said members being provided with protectors of poor conducting material.

4. A curling device comprising, in combination, a cylindrical heating element, a cooperating clamping member associated with the heating element, said last named member being formed of sheet metal bent transversely into an approximate U-shape, heat protector means along the edges of the clamping member and a heat protector secured to and extending along one side of the heating element.

5. A curling device comprising, in combination, a cylindrical heating element, a cooperating clamping member associated with the heating element, said last named member being formed of sheet metal bent transversely into an approximate U-shape, heat protec-

tor means along the edges of the clamping member and a heat protector extending along the heating element and resilient means for securing the protector in place.

6. In a curling device having an elongated cylindrical heating element provided with a pointed end, a protector comprising a bar formed from a material having poor heat conducting properties, one end of said bar being provided with a portion projecting to one side and forming a shoulder, said shoulder having a recess adapted to receive the pointed end of the heating element and resilient means attached to the other end of said protector for attaching it to the heating element.

7. In a curling device having an elongated cylindrical heating element provided with a pointed end, a protector comprising a bar formed from a material having poor heat conducting properties, one end of said bar being provided with a portion projecting to one side and forming a shoulder, said shoulder having a recess adapted to receive the pointed end of the heating element and resilient means attached to the other end of said protector for attaching it to the heating element, the side of the bar adjacent the heating element being bowed away from the heating element so that it will contact with the latter only at its ends.

8. A protector adapted to be applied to the heating element of a hair curler, comprising a bar formed from material having poor heat conducting properties, one end of said bar having means for attaching it to one end of the heating element and the other end having means for attaching it to an intermediate portion of the heating element.

9. A protector adapted to be applied to the heating element of a hair curler, comprising a bar formed from material having poor heat conducting properties, one end of said bar having means for attaching it to one end of the heating element and the other end having means for attaching it to an intermediate portion of the heating element, one side of said bar being bowed.

10. A hair curling device having a member of heat conducting material, means for heating said member, a protector comprising a member of poor heat conducting material extending along the heated member, and means for securing the protector in place.

In testimony whereof I affix my signature.

JOSEPH H. JACOBS.
